(57) **CLAIM**

The ornamental design of a sensor vault charger, substantially as shown and described.

DESCRIPTION

FIG. 1 is a top perspective view of a sensor vault charger in accordance with the present invention.

FIG. 2 is a left view thereof.

FIG. 3 is a right view thereof.

FIG. 4 is a front view thereof.

FIG. 5 is a back view thereof.

FIG. 6 is a top view thereof; and,

FIG. 7 is a bottom view thereof.

The broken lines shown in the drawings are for the purpose of illustrating portions of the sensor vault charger that form no part of the claimed design.
